UNITED STATES PATENT OFFICE.

DAVID WHITE, OF NEW YORK, N. Y., ASSIGNOR, BY MESNE ASSIGNMENTS, TO THE KNICKERBOCKER FIRE EXTINGUISHER COMPANY, OF SAME PLACE.

FIRE-EXTINGUISHER.

SPECIFICATION forming part of Letters Patent No. 578,434, dated March 9, 1897.

Application filed May 26, 1896. Serial No. 593,163. (No model.)

To all whom it may concern:

Be it known that I, DAVID WHITE, a resident of the city, county, and State of New York, have invented certain new and useful Improvements in Fire-Extinguishers, of which the following is a specification.

My invention relates to hand fire-extinguishers; and the object of the invention is to provide an efficient extinguisher wherein there are but few parts and which is simple in construction and cheap to manufacture.

To these ends my invention consists in the novel arrangement and combination of parts and to the details of construction hereinafter described and claimed.

In the accompanying drawings, which form a part of this specification, Figure 1 represents a side view, with parts broken away, of a hand fire-extinguisher made in accordance with my invention. Fig. 2 is a fragmental face view of the extinguisher looking in the direction of the arrow in Fig. 1. Fig. 3 is a vertical section of the same on an enlarged scale on the line 3 3, Fig. 2. Fig. 4 is a detail top view of the sealing-plate to be hereinafter described.

In the drawings, A designates a cylinder or main body portion of my improved hand fire-extinguisher, which may be connected with the top and bottom a b, respectively, in any suitable manner. The top a has secured to it a suitable cage c, which supports a coiled spring d to hold a valve e seated against a valve-seat f of the port to charge the fire-extinguisher. This valve-seat f is struck up from the body of the metal forming the top a of the extinguisher and is sealed by suitable means, as by a plate g, soldered in the upper portion of the port formed by the valve-seat. This plate g is preferably provided with a loose extension g', which projects from the edge thereof and which is provided with an aperture g² therein for purposes which will be hereinafter explained. At the lower end of the cylinder is a nozzle h, which is struck up from the body of the metal cylinder. This nozzle h is covered by a cap i, from which extends a handle j and a hook-like extension k on opposite sides thereof. The cap i is preferably made of metal and is soldered to the body of the cyl-

inder, as indicated at l, so that there is no liability whatever of the nozzle itself becoming injured or choked by the solder which secures the cap in place.

In use the cap i with the handle j and hook k, attached thereto, are soldered to the cylinder, so as to prevent the escape of liquid through the nozzle h. The extinguisher is next filled by forcing the valve e against the tension of its spring d, when the liquid is forced into the cylinder together with the gas for charging the same. When the cylinder has been properly filled and charged, the valve is allowed to reseat itself against the valve-seat f and the sealing-plate g is soldered to the opening or port formed by the valve-seat, so that the fire-extinguisher as a whole is securely sealed.

When it is desired to put the fire-extinguisher into operation, it is merely necessary to twist off the cap i by means of the handle j and hook-like extension k, which provide double levers therefor. The cap being soldered in the manner shown and described provides against injury to the nozzle h in twisting off or removing the cap from the nozzle. When it is desired to refill the fire-extinguisher, the hook-like extension k on the cap i can be inserted in the aperture g² of the sealing-plate and the latter can be removed therewith from the opening in the top of the cylinder, which gives access thereto.

It will be observed that by my invention I am enabled to make the body of the fire-extinguisher itself form the valve-seat of the inlet-opening and the nozzle for the ejection of the fluid, thereby greatly diminishing the cost of construction over devices wherein separate parts are provided for this purpose and at the same time overcoming the liability of leakage at the points of joinder between the auxiliary or separate parts forming the valve-seat and nozzle and the body of the extinguisher itself. Furthermore, such auxiliary parts forming the nozzle and valve-seats in fire-extinguishers heretofore made were cast of soft metal and liability of injury to such soft-metal parts was great. These disadvantages are overcome by my invention, and a simple, cheap, and efficient hand fire-extinguisher is provided.

I am aware that it is old to provide a sealed nozzle or nipple of frangible material adapted to be broken when it is desired to operate the extinguisher, and such I do not claim; but

5 What I do claim, and desire to secure by Letters Patent, is—

A hand fire-extinguisher comprising a metallic body portion, an ejecting-nozzle struck up therefrom, a cap controlling the flow of
10 liquid through said nozzle soldered to said

body portion, with means connected to said cap for removing the same, an inlet-port connected with the extinguisher, the valve-seat whereof is struck up therefrom, and a sealing-cap sealing the opening in said port, sub- 15 substantially as described.

DAVID WHITE.
